G. M. HOLLOWBACK

DENTAL OR OTHER FURNACE OR OVEN

Filed June 29, 1918

Inventor,
George M. Hollenback

By

Raymond Bent Hollenback
His Attorney

UNITED STATES PATENT OFFICE.

GEORGE M. HOLLENBACK, OF LEWISTOWN, MONTANA.

DENTAL OR OTHER FURNACE OR OVEN.

Application filed June 29, 1918. Serial No. 242,521.

To all whom it may concern:

Be it known that I, GEORGE M. HOLLENBACK, a citizen of the United States, residing at Lewistown, in the county of Fergus and State of Montana, have invented new and useful Improvements in Dental or Other Furnaces or Ovens, of which the following is a specification.

This invention relates to dental and other furnaces and ovens, and it has for its object to provide an improved device or improved apparatus of the character stated, which will be superior in point of relative inexpensiveness and simplicity, taken in connection with positiveness and reliability and precise accuracy in performance and operation, convenience in use, and length of life or durability; and which will be generally superior in efficiency and serviceability.

With the above and other objects in view, the invention consists in the novel and useful provision, formation, association, combination, relative arrangement and mode of operation and operative control of parts, members and features, all as hereinafter described, shown in the drawing, and finally pointed out in claim.

The drawing is a central vertical sectional view of an improved device or improved apparatus embodying the invention, parts being shown in elevation for clearness of illustration.

The various parts and features as disclosed in the drawing are designated by reference characters.

Referring with particularity to the drawing, the improved furnace or oven for dental or other purposes which is disclosed therein as embodying and exemplifying the invention, is provided with or formed to provide a working chamber A, within which is disposed the object, article or work to which heat is to be applied, or which is to be subjected to thermal action, the heat being so applied or provided by or at a source of heat units B, the latter being preferably disposed beneath the chamber A and its bottom member 2. The chamber A and heating chamber b within which the source of heat B is disposed, are both conveniently and inexpensively provided within a common casing 3, which is shown as cylindrical, the lower portion of such casing being cut out or notched to provide legs or supports 4,

admitting air to the heating chamber for the purpose of supporting combustion therein, depending upon the nature and character of the heat producing means B. The working chamber A is sealed off from the heating chamber b by the bottom member 2 which is a circular plate or diaphragm extending transversely of and within the casing 3. Beneath this plate or diaphragm 2 and between it and the source of heat B is disposed a baffle plate or heat distributor 4 which is preferably connected with such plate or diaphragm 2 and depends from it, producing an open air space or chamber 5 between the main body of such distributor and the plate 2, and of an area coincident with the central portion of the diaphragm 2, and coincident with as much of the area of said diaphragm as the proper distribution of the heat may require. As shown in the drawing, the distributor or baffle plate 4 is, and may conveniently be, suspended from the bottom plate 2 by a series of fingers 4^a which, by means of hooked marginal portions, 4^b, take into openings in the bottom plate 2. Such series of fingers 4^a are alternated with open spaces 4^c, to open up communication of the space between such plate 4 and such plate 2 and destroy the dead air space which would otherwise exist.

The working chamber A is provided with a closure C, which may consist of a cap 6 extending over and fitting the mouth of the chamber A, and having an annular marginal flange 6^a, overlapping the side wall of the chamber A or of that portion of the casing 3 which constitutes the lateral walls of such chamber. Fixed to such closure plate 6, and projecting both above and beneath the same, is a temperature-indicating device D, which may consist of a thermometer with Fahrenheit or other readings, and preferably has its bulb immersed in a mercury bath confined within a container d which is disposed in contact with the diaphragm 2 directly above the baffle or distributor plate 4. The portion of the thermometer having the usual readings projects above the closure plate 6, so that when the closure is in position to seal the mouth of the chamber A the readings of the thermometer may readily be noted to determine the thermal condition of the working chamber.

The source of heat B is specifically disclosed as comprising electrical resistance in a coil 7 disposed within the heating chamber *b* and adapted to be supplied with electrical energy through circuit wires 8, leading to a suitable source of electrical energy, and included within the circuit of such wires 8 and coil 7 are further circuit wires 9 leading to and in circuit with a thermostatic device E, of any preferred organization, and which has its heat-sensitive element *e* disposed within the working chamber A. By means of such thermostatic device, and its co-action with an electrical contact 10 within such working chamber, and in circuit with the circuit wires 9, the energization of the resistance coil 7 may be controlled responsive to temperatures in the working chamber A, so that a substantially constant temperature within such working chamber may automatically be maintained. It will be understood, however, that the present invention is not concerned by limitation with any such thermostatic device, and may be practiced either with or without the same.

In the use and operation of a device or apparatus embodying the invention, such as the dental furnace or oven disclosed in the drawing, and hereinabove described, (although it will be understood that this embodiment is merely illustrative and exemplary of the invention, but not exclusively so), the work or object or article to be heated is placed within the chamber A, and the closure C with its temperature-indicating device D is placed over said chamber so as to enclose the same with the work therein. The source of heat B is then rendered effective, and either with or without the automatically controlling thermostatic device E or its equivalent or substitute, imparts its heat units to the chamber A and the work therein, through the diaphragm or bottom plate 2, the baffle plate or distributor plate 4 serving to prevent a concentration of heat application directly at the center of the chamber A or at the point of disposition therein of the heat-responsive bulb of the thermometer. Of course in the use of the resistance coil 7 such heat-concentration is less pronounced than in the use, for instance, of a Bunsen burner, disposed centrally of the chamber *b*, in the manner indicated by dotted lines in the drawing. It will be understood that such baffle or distributor is utilized when necessary to cause an even diffusion of the heat from such source of heat B as may be employed, and its even distribution throughout the working chamber A, which, as indicated may have an asbestos or like lining at its sides and top. As heat rises in the chamber A, the indicating column in the thermometer or heat-indicating device D ascends, and when the proper

reading has been reached in this manner, the production of heat is automatically discontinued, as by a thermostatic device, or any equivalent or substitute thereof, and such heat production is re-established, in intermittent action, as requisite to maintain a constant temperature within the chamber A. Or, the production of heat may be terminated and renewed voluntarily, where no such automatic controlling means, such as E, is employed. This operation is carried on, namely, this maintenance of an accurately constant temperature in the working chamber A, as long as the work, therein is subjected to thermal action. In the use of the apparatus as a dental oven or furnace, we will assume that the work in the chamber A comprises a metallic flask containing a wax inlay pattern invested in a hardened plastic substance. The constantly maintained temperature in the working chamber is effective to burn out and eliminate the wax contained in the pattern in the surrounding substance, leaving a mold to be utilized in casting the inlay. This is but one illustration of the use of this apparatus, and its highly advantageous utility in the provision of a working chamber A in which a definite temperature is to be precisely and accurately maintained. It has been found in practice that unless such constant temperature is maintained, for instance in the production of an inlay mold, as described, that the initially plastic material in which the mold has to be formed by the burning out of the wax, becomes so over-expanded or heat-affected, that the subsequent shrinkage fails to restore the wax-containing cavity, which becomes the mold, to its normal and proper formation and dimensions, thus producing a distortion and error of formation which in turn produces an incorrectly shaped and proportioned inlay. It will be readily understood that in work of this character the slightest departure from correct dimensions and conformation will be fatal.

It will be manifest that many variations, modifications, changes and departures may be made, in adapting the invention to varying conditions of use and service, and in practicing the invention, under varying conditions, and for different purposes, in departures from the specific disclosures of the drawing and the preceding description, and statement of operation and mode of use, without departing from the true spirit of the invention and a fair interpretation thereof.

Having thus disclosed my invention, I claim and desire to secure by Letters Patent:

In a dental oven, the combination with a chambered work-holding member, of means supporting said member in elevation, a closure for said member, and means for apply-

ing heat to said member; there being a flat heat distributing plate pendent from the base of said work-holding member and interposed between the source of heat and base 5 of the work-holding member; said oven likewise being provided with a thermometer mounted upon said closure and having its heat sensitive element within the chamber of the work-holding member and in contact 10 with the base thereof whereby the temper-

ature within the chambered work-holding member is denoted exteriorly of the oven.

In testimony whereof, I have signed my name to this specification in the presence of two subscribing witnesses.

GEORGE M. HOLLENBACK.
